(57) **CLAIM**

The ornamental design for a confinement liner for a substrate processing chamber, as shown and described.

DESCRIPTION

FIG. 1 is a top isometric view of a confinement liner for a substrate processing chamber showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left elevation view thereof;

FIG. 7 is a right elevation view thereof; and,

FIG. 8 is an enlarged cross-sectional view taken along line 8-8 of FIG. 2.

The broken lines shown in the drawings represent portions of a confinement liner for a substrate processing chamber that form no part of the claimed design.
